UNITED STATES PATENT OFFICE

EMILE HENRI COQUILLE, OF PARIS, FRANCE, ASSIGNOR TO SOCIETE ANONYME DES USINES CHAUSSON, OF ASNIERES, SEINE, FRANCE

WHEEL SUPPORT

Application filed July 16, 1931, Serial No. 551,238, and in France August 13, 1930.

The object of my invention is a tilting support for motor car spare wheels, which may be combined with a chest, the door of which tilts with said support.

5 One of the chief characteristics of my invention consists in that said support is jointed, at two points suitably distant from each other, to levers or guides which cause said joints to move along different fixed paths in 10 such manner that, near the closed position of the chest, the position of the center of gravity of the device with regard to its instantaneous center of rotation may be such that the torque due to gravity will tend to bring the 15 wheel into a vertical plane and to maintain it there, i. e., to close the chest when the support is integral with one door of said chest.

According to another characteristic of my 20 invention, the moving system is balanced by one or more springs connected to said device in such a way that, as the tilting takes place, the antagonistic force of said springs shall vary in power, in the same proportion as the torque due to gravity, when said torque acts 25 in the direction in which the chest is opened.

Other characteristics of my invention will appear from the following description of 30 preferred embodiments of my invention with reference to the accompanying drawings, given merely by way of example and in which:

Fig. 1 is a vertical section of a device according to my invention, in the position in 35 which the chest is closed, the support being integral with a door of said chest;

Fig. 2 is a vertical section of the same device, in the position for which the moving device is substantially in unstable equilibrium;

Fig. 3 is a view similar to Figs. 1 and 2, the 40 same support being shown completely tilted;

Fig. 4 is a plan view of the support in the position shown in Fig. 3;

Fig. 5 is an elevational view of another mode of mounting the chest door;

Fig. 6 is an elevational view of another arrangement for jointing the tilting support to the frame of the car.

In the embodiment shown in Figs. 1 to 4, a chest 8 and two angle plates 2, which support the tilting device, are fixed to a cross

member 1, integral with the frame of the car.

Two links 3 and 4 are pivotedly connected, at one end to angle plates 2, at the other end to arms 5. Said arms 5 are integral with a false hub 9 which supports the spare wheels 55 10 and 11. Preferably, door 7 of chest 8 will be fixed to arms 5, through adjustable angle plates 6, in the usual way.

Owing to springs 13, the tilting device can be constantly balanced throughout its rotation. To this effect, springs 13 are connected to the moving organs in such a way that the power of said springs will vary in accordance with that of the antagonistic torque due to gravity. In the example shown in Figs. 1 to 65 4, springs 13 are fixed on the one hand to arms 5 (or to a cross member integral with said arms) and, on the other, to levers 12 which pivot about the axis of articulation of links 4 with arms 5. Levers 12 are provided 70 with a heel adapted to bear against a tubular brace 14, which may be fixed, say by soldering, to links 4.

The device, according to my invention, 75 operates as follows:

The position of the axes of oscillation of links 3 and 4, as also the length of said links and the distance of their axes of articulation on arms 5, are so chosen that, when the tilting device is in the position which corresponds to the closing of chest 8 and during a fraction 80 of the course it follows when starting from the latter position, the center of gravity G of the whole tilting device is on the same side as chest 8, with respect to the vertical line which 85 passes through the instantaneous center of rotation of said device (point at which the axes of links 3 and 4 intersect each other).

As a result, in the above indicated positions of the tilting system, the very weight of the 90 device applies door 7 against chest 8 and holds it in the closed position. Therefore, whatever may be the number and weight of the 95 spare wheels, the tilting device, as a body, tends to close the chest and not to open it, through the action of gravity.

As the moving device is further tilted, the instantaneous center of rotation of said device is displaced, because the links rotate, through 100 different angles, about their respective axes

of oscillation. The center of gravity G of the device is also displaced, following on ascending curve GH. At a certain point, the instantaneous center of rotation and the center of gravity G are on the same vertical line and the device is in unstable equilibrium (as shown in Fig. 2, in which the center of gravity G of the device is at H, i. e., at the highest point of its path GHJ).

10 The moving device continuing its displacement towards the opened position of chest 8 the center of gravity of said device moves to the other side of the vertical line which passes through the instantaneous center of rotation 15 and, therefore, the torque due to gravity accentuates that opening motion. As soon as the device is in equilibrium, the heels of brackets 12 coming in contact with bracing member 14 cause levers 12 to follow links 4 20 in their rotary motion. This causes an elongation of springs 13, the increasing tension of which insures the balancing of the system in the second part of the opening motion. When the center of gravity G coincides with 25 point J, links 4 are applied against links 3, thus stopping the whole.

Fig. 5 shows another mode of mounting door 7 of chest 8, according to which said door 7, instead of being integral with the support, is articulated to said support through links 15. In this case, door 7 is mounted 30 on chest 8 through a hinge 16.

Of course, links 3 and 4, through which the support is articulated to the frame, may be 35 replaced by any other connecting organs such that the trajectory of the center of gravity may have, as that shown in Figs. 1 and 2, a first ascending motion. For example, in Fig. 6, arms 5 are articulated to link 3, which 40 is itself jointed to the frame. Pins, or fingers, 16, integral with said arms 5, are adapted to move in fixed slides 17, suitably curved.

While I have disclosed what I deem to be 45 preferred embodiments of my device, I do not wish to be limited thereto, as there might be changes made in the arrangement, disposition and form of the parts, without departing from the principle of my invention as comprehended within the scope of the appended 50 claims. In particular, the disposition and form of the balancing springs may differ from those above described.

What I claim is:

55 1. A support for motor car spare wheels comprising, in combination, means adapted to rigidly support the spare wheels, at least one lever integral with said means, at least one member adapted to be rigidly secured to 60 the car frame, a plurality of links pivoted at one end to said member and at the other end to said lever, at least one spring connected at one end to said lever, and means for connecting the other end of said spring 65 to said member in such a manner that the

resisting strength of said spring varies in accordance with the torque due to gravity.

2. A support for motor car spare wheels comprising, in combination, means adapted to rigidly support the spare wheels, at least 70 one lever integral with said means, at least one angle plate adapted to be rigidly secured to the car frame, two links disposed one above the other and each pivoted at one end to said angle plate and at the other end to said lever, the center of gravity of the movable system being on the same side of the vertical plane 75 passing through the instantaneous center of rotation of said system as said angle plate for substantially vertical positions of the 80 spare wheels, at least one spring connected at one end to said lever, and means for connecting the other end of said spring to said member in such a manner that the resisting 85 strength of said spring varies in accordance with the torque due to gravity. 90

3. In combination with a support according to claim 1, a chest and means for connecting the door of said chest to said lever.

4. In combination with a support according to claim 2, a chest and means for connecting the door of said chest to said lever.

5. In combination with a support according to claim 2, a chest and means for rigidly securing the door of said chest to said lever. 95

6. In combination with a support according to claim 2, a chest, and a plurality of small connecting rods for connecting the door of said chest to said lever.

7. A support for motor car spare wheels 100 comprising, in combination, means adapted to rigidly support the spare wheels, at least one lever integral with said means, at least one angle plate adapted to be rigidly secured to the car frame, two links disposed one 105 above the other and each pivoted at one end to said angle plate and at the other end to said lever, the center of gravity of the movable system being on the same side of the vertical plane passing through the instantaneous 110 center of rotation of said system as said angle plate for substantially vertical positions of the spare wheels, at least one spring connected at one end to said lever, a bar extending at right angles to the lower link and carried thereby, at least one bent lever pivoted to the outer end of the last mentioned link and connected to the other end of said spring, and a heel on said bent lever adapted to engage said bar. 115

8. A support for motor car spare wheels comprising in combination a car frame, means adapted to rigidly support the spare wheels, a stop member on said frame, on which said supporting means is adapted to bear in a substantially vertical position, a link pivoted at one end to said frame and at the other end to said spare wheel supporting means, a pin engaged in said supporting means and guiding means provided on said 125 130

car frame adapted to guide said pin in such manner that the centre of gravity of the system formed by the spare wheels with its supporting means is situated on the same side of the vertical plane passing through the instantaneous centre of rotation of said system as said stop member for substantially vertical positions of the spare wheels.

In testimony whereof I have signed my name to this specification.

EMILE HENRI COQUILLE.
